UNITED STATES PATENT OFFICE

WALTER E. HENRY, OF BALTIMORE, MARYLAND

CROSSHEAD

Application filed February 16, 1927. Serial No. 168,715.

This invention relates to improvements in locomotive cross heads and their guides, the general object of the invention being to provide means for taking care of all wear, both lateral and vertical that appears between the shoes and the guide bars.

Another object of the invention is to so form the parts that adjustment can be made to take up wear by moving the shoes towards the guide bar and also by moving the bars towards the shoes, thus giving a double adjustment which will take care of about $1\frac{1}{8}$ " of wear before repairs are necessary so that the life of the shoes and guide bars is greatly increased.

Another object of the invention is to so form the parts that the wedges are clamped in adjusted position by the securing bolts and the wedges will remain in position even though some of the bolts should work loose.

Another object of the invention is to provide rack means for moving the wedges, portions of which are carried by some of the bolts.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an elevation of the improved cross head.

Figure 2 is a section on line 2—2 of Figure 3.

Figure 3 is an end view with the guides shown in section.

Figure 4 is a section on line 4—4 of Figure 1.

Figure 5 is a section on line 5—5 of Figure 1.

Figure 6 is a perspective view of one of the wedges.

Figure 7 is a fragmentary view of a modification.

Figure 8 is an edge view of Figure 7.

In these drawings, 1 indicates the body of the cross head and 2 indicates the shoes for engaging the guides 3. The shoes are connected with the body by means of the bolts 6, these bolts passing through elongated holes 55 formed in the shoes so that the shoes have limited vertical movement relative to the body. Wedges 8 are placed between the shoes and body to adjust the shoes in relation to the body and these wedges are of angle shape in cross section, as clearly shown in Figure 6. Each wedge is provided with the rack teeth 9 on a portion of its enlarged end and the front bolt of each row of bolts is formed with the two sets of teeth 10 for engaging the rack teeth so that when this bolt is turned by a wrench or the like engaging the square end 10' of the bolt, the two wedges engaged by the bolt will be moved in one direction or the other according to the direction of rotation of the bolt.

Thus when the shoes need adjusting, it is simply necessary to loosen the nuts of the bolts and then to turn the front bolts to move the wedges inwardly to force the shoes outwardly and then the nuts of the bolts are tightened to hold the shoes in adjusted position. As will be seen from Figures 4 and 5, by making the wedges of angle shape in cross section, portions of the wedges will be 80 clamped between the body and shoes so that the wedges will be firmly held in adjusted position. Of course, the engagement of the teeth of the front bolts with the rack teeth of the front wedges will also act to hold the 85 wedges in adjusted position.

In order to permit the front bolts to be placed in position, I form a recess 11 in each wedge at the inner end of the teeth bearing part so that the bolt will pass through this recess without interference on the part of the wedge. A projection 12 is formed at the small end of each wedge, which will strike a bolt and thus limit the movement of the wedge in one direction while a pin or projection 13, carried by the shoe, limits the movement of the wedge in the opposite direction by the small end of the wedge striking the said pin.

Figures 7 and 8 show a modified form of the

invention in which the two upper and the two lower wedges are connected together by the bight 14 so that each pair of wedges forms a U-shaped member.

8 As shown in the drawings, the wedges are put in place from the front end of the cross head, which is more accessible than the rear and this will permit greater space at the rear of the cross head for the main rod.

10 From the foregoing, it will be seen that I have provided means whereby the shoes can be easily and quickly adjusted on the cross head and the shoes are firmly fastened in adjusted position through the clamping action 15 of the bolts and also through the toothed connection between the front bolts and the wedges.

I also make the guide bars 3 with V or wedge-shaped inner faces, as shown at 3' 20 which engage V-shaped recesses 2' formed in the outer faces of the shoes. By this arrangement the adjustment of the shoes towards the guide bars will take up all wear, lateral as well as vertical, and it also permits 25 wear to be taken up by adjustment of the bars toward each other. This will enable the bars to be adjusted toward each other after the shoes have been adjusted to their full extent so that a double adjustment is 30 secured which will take care of about $1\frac{1}{8}$ " of wear before repairs are necessary so that the life of the shoes and guide bars is greatly increased. When the limit of adjustment of the shoes has been reached the wedges are 35 returned to their original positions and then the guide bars are moved against the shoes, it being understood that the bars as now arranged are capable of this adjustment. Then the shoes can be adjusted by their wedges a 40 second time.

As will be seen the wedges are then held in place by the bolts even though some of the bolts should work loose.

To adjust the cross head the bolts are all 45 loosened to release the wedges and then the wedges are adjusted, after which the bolts are tightened. The plain bolts must be tightened first so that they will lock the wedges in position and to prevent them from 50 moving when the adjusting bolts are tightened.

It is thought from the foregoing description that the advantages and novel features of my invention will be readily apparent.

55 I desire it to be understood that I may make changes in the construction and in the combination and arrangement of the several parts, provided that such changes fall within the scope of the appended claims.

60 What I claim is:

1. In a cross head of the class described, wedges for adjusting the shoes on the head, each wedge having a rack part, bolts for connecting the shoe with the head, at least one of 65 the bolts having teeth engaging the rack

teeth for adjusting the wedges when the bolts are turned.

2. In a cross head of the class described, wedges for adjusting the shoes on the head, each wedge being of angle shape in cross section with a portion thereof extending vertically between a portion of the body and a portion of the shoe, bolts for connecting the shoes with the body, said bolts setting up a clamping action to clamp the vertical parts 70 of the wedges between the body and the shoes, each wedge having rack teeth thereon and at least one of the bolts having annular rows of teeth for engaging the rack teeth to adjust the wedges when the bolts are turned.

3. A cross head of the class described comprising a body and a pair of shoes, each shoe having elongated holes therein, bolts for connecting the shoes with the body, said bolts passing through the elongated holes in the shoes, wedges of angle shape in cross section with portions of the wedges extending vertically between parts of the body and parts of the shoes so that when the bolts are tightened, the vertical portions of the wedges will be clamped between the body and shoes, rack teeth on the wedges and at least one of the bolts having teeth thereon for engaging the rack teeth so that when these bolts are rotated 80 the wedges will be adjusted.

4. A cross head of the class described comprising a body and a pair of shoes, each shoe having elongated holes therein, bolts for connecting the shoes with the body, said bolts passing through the elongated holes in the shoes, wedges of angle shape in cross section with portions of the wedges extending vertically between parts of the body and parts of the shoes so that when the bolts are tightened, the vertical portions of the wedges will be clamped between the body and shoes, rack teeth on the wedges, at least one of the bolts having teeth thereon for engaging the rack teeth so that when these bolts are rotated 90 the wedges will be adjusted.

5. A cross head of the class described comprising a body and a pair of shoes, each shoe having elongated holes therein, bolts for connecting the shoes with the body, said bolts passing through the elongated holes in the shoes, wedges of angle shape in cross section with portions of the wedges extending vertically between parts of the body and parts of the shoes so that when the bolts are tightened the vertical portions of the wedges will be clamped between the body and shoes, rack teeth on the wedges, at least one of the bolts having teeth thereon for engaging the rack teeth so that when these bolts are rotated 100 the wedges will be adjusted and a connecting piece between the wedges of each pair.

6. A locomotive crosshead including a body portion, shoes at the top and bottom 110

thereof, a U-shaped wedge interposed between one of the shoes and the body portion of the crosshead, a rack formed on said wedges, and a pinion for cooperation with said rack.

7. A locomotive crosshead including a body portion, shoes at the top and bottom thereof, a U-shaped wedge interposed between one of the shoes and the body portion of the crosshead, a rack disposed longitudinally of said wedge, and a pinion for cooperation with said rack.

8. A locomotive crosshead including a body portion, shoes at the top and bottom thereof, a U-shaped wedge interposed between one of the shoes and the body portion, a rack associated with said wedge, a shaft mounted on said body portion, and a pinion fixed to said shaft for cooperation with said rack.

9. A locomotive crosshead including a body portion, shoes at the top and bottom thereof, a U-shaped wedge interposed between one of the shoes and the body portion, a rack associated with said wedge, a transversely disposed shaft mounted on said body portion, and a pinion fixed to said shaft for cooperation with said rack.

10. A locomotive crosshead including a body portion, shoes at the top and bottom thereof, a wedge interposed between one of the shoes and the body portion, a longitudinally extending rack formed on said wedge, a shaft mounted in said body portion, and a pinion fixed to said shaft for cooperation with said rack.

11. A locomotive crosshead including a body portion, shoes mounted on the top and bottom thereof, a U-shaped wedge interposed between one of the shoes and the body portion, a rack integrally formed on said wedge and extending between the prongs thereof, a transversely disposed shaft mounted for rotation in the body portion of said crosshead, a pinion fixed to said shaft for cooperation with said rack.

12. A locomotive crosshead including a body portion, shoes at the top and bottom of said body portion, a wedge interposed between one of the shoes and the body portion of the crosshead, a rack associated with said wedge, rotatable means disposed transversely of said body portion for cooperation with said rack, and means for locking said rotatable means against rotation.

13. A locomotive crosshead including a body portion, shoes at the top and bottom thereof, a U-shaped wedge interposed between one of the shoes and the body portion of the crosshead, one limb of the wedge being of angle shape in cross section with a portion thereof extending vertically between a portion of the body and a portion of the shoe and bolts for connecting the shoes with the body, the bolts of the shoe with which the wedge

is associated setting up a clamping action to clamp the vertical portion of the wedge between the body and the shoe.

In testimony whereof I affix my signature.

WALTER E. HENRY.
